UNITED STATES PATENT OFFICE

125,660

DESIGN FOR A HANDBAG FRAME

Charles Goldstein, New York, N. Y., assignor to The J. E. Mergott Company, Newark, N. J., a corporation of Delaware

Application October 22, 1940, Serial No. 95,997

Term of patent 7 years

To all whom it may concern:

Be it known that I, Charles Goldstein, a citizen of the United States of America and a resident of the Borough and county of Bronx, city and State of New York, have invented a new, original, and ornamental Design for Handbag Frames, of which the following is a specification, reference being had to the accompanying drawing, forming part thereof.

In the drawing:

Fig. 1 is a perspective view partly open of a handbag frame embodying my design;

Fig. 2 is a top plan view of the handbag frame in closed condition;

Fig. 3 is a front elevational view of the handbag frame in closed condition;

Fig. 4 is an end view thereof.

I claim:

The ornamental design for a handbag frame, substantially as shown and described.

CHARLES GOLDSTEIN.
